UNITED STATES PATENT OFFICE.

HAROLD C. SHIPMAN, OF OTTAWA, ONTARIO, CANADA.

KEYLESS LOCKING DEVICE.

1,140,919.

Specification of Letters Patent. Patented May 25, 1915.

Application filed December 8, 1913. Serial No. 805,454.

To all whom it may concern:

Be it known that I, HAROLD C. SHIPMAN, a subject of the King of Great Britain, and resident of the city of Ottawa, Province of 5 Ontario, Canada, have invented certain new and useful Improvements in Keyless Locking Devices, of which the following is a specification.

The invention relates to improvements in 10 keyless locking devices, as described in the present specification, and illustrated in the accompanying drawings that form part of the same.

The invention consists essentially of the 15 novel arrangement and construction of parts as hereinafter described, whereby the latch bow or bolt of a lock is engaged by a lock-disk rotatably arranged in a casing, and carrying depressible pins engaged by de- 20 pressible buttons arranged in the casing to release the pins from retaining recesses.

The objects of the invention are to provide a lock of simple, durable and compact construction, which will operate without a 25 key, and without giving indication of the position of the locking parts.

In the drawings, Figure 1 is a perspective view of the lock, showing approximately three-quarters of the front cover-plate re- 30 moved and portions therebeneath broken away. Fig. 2 is a cross sectional view on the line 2—2 of Fig. 1. Fig. 3 is a perspective detail view of one of the ring-members. Fig. 4 is a perspective detail view of the 35 pair of the disk-members. Fig. 5 is a perspective detail view of one of the buttons. Fig. 6 is a perspective detail view of one of the spring retaining washers of the disk-member and the spring therefor. Fig. 7 is 40 a perspective detail view of one of the spring-washers. Fig. 8 is a perspective detail view, showing the locking device attached to a trunk or the like. Fig. 9 is a perspective detail view, showing the lock- 45 ing device attached to a mail-bag or the like.

Like numerals of reference indicate corresponding parts in each figure.

Referring to the drawings, Figs. 1-7 illustrate one embodiment of my invention 50 adapted to a padlock formed from stamped parts as being preferable for cheap construction, though it must be understood that

the number of parts as hereinafter described are not of necessity separate, and in many instances are riveted one to the other to 55 form substantially an integral piece.

The casing 1 of the lock is formed substantially circular with the side-flange 2 extending therearound, said side-flange having the hinge opening 3 and the opening 4 60 at the top thereof for the lock-bow 5. The casing 1 further has a central orifice 6 therethrough, and a number of orifices 7 therethrough adjacent the edge and radially spaced around the casing on the lower half 65 thereof. A cover plate 8 is secured to the side flange 2 of the casing 1, said cover-plate having the central orifice 9 and the radially spaced orifices 10 therein similar to the casing 1. The locking member, or bow 5 of 70 the lock is hinged at one extremity on the rivet 11 inserted through suitable orifices in the casing and cover-plate immediately inside the hinge opening 3, the latch end of said bow hooking through the opening 4, 75 and having the hooked end 12. A center rivet 13 is inserted in the lock with the reduced ends 14 extending through the orifices 6 and 9, and riveted therein to retain the spring washers 15 in position. The spring 80 washers 15 have the spring arms 16 extending radially therefrom and spaced to correspond with the radially spaced orifices 7 and 10, and are secured by the reduced ends 14 of the rivet 13, which passes through the 85 central orifice 17 in the spring washers, and securely fastens them between the larger central portion of the rivet 13 and the casing 1 and plate 8.

In each of the orifices 7 and 10 in the casing and cover respectively, buttons 17^a are placed, having the ends 18 protruding outwardly through the orifices, and the corresponding ends 19 extending inwardly in the casing on each side of the collars 20, certain 90 of said collars fitting immediately under the extremities of the spring-arms 16, whereby the ends 18 which protrude through the orifices are resiliently held to their position with the collars 20 bearing against the casing and the cover-plate on the inner sides thereof.

The inner ends 19 of the buttons extend 100 through two segmental rings 31 fitted on the

inner side of the casing and cover respectively, said rings having the angularly turned ends 32, which extend through suitable corresponding openings in the casing 5 and cover-plate, thereby fixedly securing the rings therein. The openings in which the said upturned ends 32 are secured are not shown in the drawings, but constitute a common means for securing elements together.

The rings 31 have the orifices 33 therethrough corresponding to the orifices 7 and 10, and the recesses 34 about said orifices on the sides of the rings next the casing and 15 cover-plate respectively, whereby the spring-fingers 16 may extend into the recesses over certain of the collars 20 on the buttons 17^a as hereinafter mentioned, and permit the said collars 20 of the buttons to move to the 20 extent of the depth of the recesses, the ends 19 passing into the orifices 33 in the bed of said recesses. A pair of locking-disks 21 having the central orifices 22 therethrough are rotatably mounted between the ring segments 31 and on the center rivet 13, said disks being cut away at 23, and having the catches 24 formed on the top thereof to interlock with the hook 12 of the bow as hereinafter described. The disks 21 have the 30 orifices 25 therethrough corresponding to the orifices 33 in the ring segments, and further are spaced slightly apart by the washers 26 riveted therebetween. The washers 26 are provided with slots 27 whereby flat springs 35 28 having the turned ends 29 may be secured between the washers with the turned end extending into one of the slots 27, whereby the spring is held in position extending radially from the washer and midway between the 40 disks 21. The springs 28 extend outwardly past the orifices 25 in the said disks 21, and short pins 30 are inserted through certain of the orifices 25, whereby they are spring held with the outer ends thereof extending 45 beyond the outer faces of the disks.

The pins 30 are preferably three or four in number, and are arranged as desired about the disks with the corresponding flat springs, and projecting either toward the 50 back casing or cover plate of the lock, and interlocking with the segmental rings 31, that is, they project into the corresponding orifices 33 in the segmental rings, thereby preventing the locking disks from rotating.

55 In the closed position of the lock as shown in Fig. 1, the hooked end of the bow extends into the casing, and is caught onto the catches 24 of the disks, said disks being prevented from rotating by the interlocking pins as hereinbefore mentioned. The disks however have the spring 36 encircling the center rivet 13, one arm of said spring being hooked into the lug 27^a from the hinge knuckle of the bow 5, whereby a normal

spring pressure is exerted on the bow to flip 65 the same open from the lock, and the other leg of said spring being fastened to the pin 37 on the disks, whereby a constant spring pressure is exerted on the disks to rotate the same counter-clockwise. It may be here 70 mentioned that a short section 38 is cut from the periphery of the disks, and an up-turned lug 39 from one of the rings projects thereinto, whereby the rotation of the disks within the casing is limited to slightly less than 75 the distance between the buttons arranged therein.

The pins 30 as hereinbefore mentioned are preferably three or four in number, and may extend toward either the casing or cover 80 plate of the lock as desired, and into the corresponding orifices 33 in the rings to hold the lock in closed position, and it is necessary to have the end 19 of each button 17 which is opposite a pin 30 shorter by the length of 85 the pin which projects into the orifice 33 in the ring, so that on pressing any one of the buttons 17 which is opposite a pin 30, the button will move just far enough to bring the pin flush with the inner face of the segment ring, so that when the proper buttons are pressed about the lock, that is, each one opposite a pin, all the pins carried by the disks will be moved flush with the face of the rings, and permit the disks to be moved 90 by the spring 36 in the direction counter-clockwise, and release the hooked end of the bow, so that the same will spring open.

In the above manner the pressing of the proper buttons forming a known combination will open the lock, but in the event of a wrong button being pressed, the inner end 19 thereof is of sufficient length to extend through the orifice 33 in the ring, into the corresponding orifice 25 in one of the disks, and thus hold the disks in locked position. It is therefore necessary that only the proper buttons be pressed, and it will be further readily understood that the buttons at all 100 times are returned by the spring arms controlling the same to their normal position, whether the lock is open or closed, so that it is impossible at any time to read the combination of buttons that control the locking pins.

110 When the lock is open the disks rotate to the extent allowed by the upturned lug 39 projecting from the ring 31 into the notch 38 on the periphery of the disk, and when it is desired to close the lock it is only necessary 115 to spring the bow into the casing, whereby the hooked end of the bow contacts with the disks adjacent the catches thereon, and rotate the same in clockwise direction until the hooked end of the bow is caught under 120 the catches on the disks, and the locking pins have been carried by the rotation of the disks to register with the orifices 33 in the 125

rings into which they spring, and again hold the lock in closed position.

It must be understood that the lock as hereinbefore described particularly refers to 5 a pad-lock preferably formed of pressed sheet metal, though the said lock may be cast or formed in various ways to operate on substantially the same principle and have the same operative parts. Furthermore, the essential locking mechanism comprising the 10 locking disk-member and casing buttons, may be employed in connection with an ordinary spring latch-bolt, to operate the same in a manner suitable for a lock as ordinarily used on doors, or may be readily arranged 15 to operate as a locking device on trunks, mail-bags or in fact any meeting parts to be locked together. That is to say, the essential features of the invention constitute the particular arrangement of locking-pins and de- 20 pressible buttons, whereby a certain predetermined combination must be known, in order that certain selected buttons may be pressed to release the locking-pins without 25 having any one or more buttons interfere with the locking-member or disk, whereby the same may be released to open the lock.

Fig. 8 illustrates my invention adapted for use with a trunk, or other similar construction; a locking member 40 being provided for ready attachment to the trunk lid.

Fig. 9 illustrates my invention applied to a mail bag; a locking member 41 being pivotally connected to any usual form of locking bar 42 of said bag.

I therefore do not wish to be confined in this respect to the particular arrangement or construction of parts as preferably shown and described in this present application.

40 What I claim as my invention is:

1. In a lock, the combination of a locking member, a casing provided with apertures, a disk shiftably mounted in said casing and provided with apertures adapted to register 45 with such casing apertures, means on said disk for lockingly engaging said locking member, pins yieldingly supported in certain apertures of said disk, buttons yieldingly supported in certain apertures of said 50 casing in engagement with said pins, and buttons yieldingly supported in other apertures of said casing and adapted to lockingly engage the corresponding apertures of said disk.

55 2. In a lock, the combination of a locking member, a casing provided with apertures, a disk shiftably mounted in said casing and provided with apertures adapted to register with such casing apertures, means on said 60 disk for lockingly engaging said locking member, pins supported in certain apertures of said disk, means for yieldingly maintaining said pins within the corresponding apertures of said casing, buttons engaging said

pins for shifting the latter from such casing 65 apertures, and buttons yieldingly supported in certain apertures of said casing and adapted to lockingly engage the corresponding apertures of said disk.

3. A keyless locking device comprising a 70 casing having lateral orifices radially spaced about each side thereof, a locking member hinged at one extremity thereof to said casing, a disk rotatably mounted in said casing and carrying a hook interlocking with the 75 free end of said locking member and having lateral orifices radially spaced thereabout and registering with the orifices in said casing, pins resiliently carried in certain of the orifices in said disk, buttons resiliently carried in certain of the orifices in said casing and contacting with the pins in said disk to release the same from said casing and buttons, resiliently carried in the remaining orifices in said casing and engaging with the 85 orifices in said disk to interlock with the same.

4. A keyless locking device comprising a 90 casing having a plurality of lateral orifices radially spaced thereabout, a locking member hinged at one end thereof in said casing, a ring section secured within said casing and having a plurality of lateral orifices, radially spaced thereabout and recesses on the side thereof next the casing and 95 about the orifices therethrough, buttons spring held in said orifices and having a collar portion movable within the recesses whereby the inner end of said buttons may project through the orifices 100 in said ring sections, a disk rotatable within said casing and interlocking with said locking member and having lateral orifices therethrough and a plurality of pins resiliently held in the orifices in said disk and interlocking with certain of the orifices in said 105 ring section.

5. A keyless locking device comprising a 110 casing having a plurality of lateral orifices spaced radially about the sides thereof, a locking member hinged at one extremity thereof to said casing and hooking into said casing at the opposite extremity, a plurality of button-pins having collars intermediate of the length thereof and extending outwardly through the orifices in said casing, spring-fingers secured in said casing and contacting with the inner sides of the collars of said buttons, ring sections having lateral orifices therethrough and recessed about said orifices and fitting over the inner ends of said pins and secured from rotation within said casing, a pair of disk-members centrally mounted in said casing and rotatable to a limited extent therein and spaced one 115 from the other and having lateral orifices therethrough, means on said disks for lockingly engaging said locking member, spring- 120

fingers radially secured between said disk-members and pins arranged in certain of the orifices of said disk-members and resiliently held by the springs of said disk-members into interlocking engagement with certain of the orifices in said ring sections.

Signed at the city of Ottawa, Canada,
this 26th day of August, 1913.

HAROLD C. SHIPMAN.
